MARKING WHEEL ATTACHMENT FOR AN INK MARKER

John D. Locatelli, 4014 35th Ave. SW.,
Seattle, Wash. 98126

Filed May 15, 1970, Ser. No. 23,019

Term of patent 14 years

Int. Cl. D19—06

U.S. Cl. D74—13

FIG. 1

FIG. 2

FIG. 1 is a side perspective view of a marking wheel attachment for an ink marker; and

FIG. 2 is a perspective view on larger scale of the side opposite to that of FIG. 1.

I claim:

The ornamental design for a marking wheel attachment for an ink marker, substantially as shown.
